METHOD AND APPARATUS FOR PEENING THE INSIDE OF TUBES AND OTHER HOLLOW BODIES

Thomas Robinson, New York, N. Y., assignor to
Lancaster Processes, Inc., New York, N. Y., a
corporation of New York

Application December 22, 1944, Serial No. 569,382

24 Claims. (Cl. 29—90)

1

The present invention relates to method and apparatus for peening metal surfaces, and particularly for peening the inner surfaces of hollow members.

The beneficial results obtained by peening metal surfaces have been known since the early days of metal working. The ancient sword makers and village blacksmiths long ago recognized that greater strength could be obtained by cold hammering or peening the surfaces of parts subject to heavy stress. More recently it has been discovered, or rediscovered, that peening greatly increases the resistance to fatigue and resistance to destructive corrosion.

The peening of external surfaces has been widely practiced and presents no particular difficulties. However, the peening of inside surfaces of hollow bodies, as for example, the inside of a tubular member, has always presented a difficult problem as the inaccessibility of such surfaces prevents the use of available peening methods. In many instances it is even more desirable to peen the inside surface of an article than the outside surface. For example, by peening the inner surface of a pipe, its resistance to scaling and corrosion, as well as its resistance to erosion, can be greatly increased. However, no means has heretofore been available for satisfactorily peening the inner surfaces of pipes or other hollow articles.

It is an object of the present invention to provide a novel method of peening metal surfaces. A further object of my invention is to provide a novel method of peening the inside surfaces of tubes and other hollow articles. The term "tube" is used generically in the present specification and claims to include pipes, casings, piling, and other tubular members.

Another object of my invention is to provide a method and apparatus for peening the inside surfaces of tubular and other hollow members efficiently, rapidly and economically on a commercial scale. A further feature of the invention is that the intensity and distribution of the peening action is subject to control, so that the entire inner surface can be peened uniformly to any desired degree. Alternatively, the peening action can be confined to selected areas or can be of greater intensity or duration in certain areas than in others.

Other objects and advantages of my invention will be apparent from the following description and claims, in conjunction with the accompanying drawings, which illustrate by way of example, selected embodiments of apparatus for peening the inside of a tube.

In the drawings,

Fig. 1 is a side elevation of apparatus for carrying out my invention.

Fig. 2 is a cross section taken approximately

on the line 2—2 in Fig. 1, and showing one of the supporting and vibrating units of the apparatus in end elevation.

Fig. 3 is a side elevation of one of the supporting and vibrating units.

Fig. 4 is an enlarged cross section through a tube being peened, and showing one form of peening means inside the tube.

Fig. 5 is a fragmentary longitudinal section through one end of the tube and showing another form of peening means.

Fig. 6 is a cross section taken approximately on the lines 6-6 in Fig. 5.

In accordance with my invention the inside surface of a hollow member is peened by introducing peening elements into the interior of the hollow member, and vibrating the member to produce repeated impact between the peening elements and the inner surface of the hollow member. The peening elements are of such nature as to produce a true peening action such as that produced by a peening hammer, as distinguished from grinding, scouring or abrading. The impact surfaces of the peening elements should hence be smooth and should preferably be surfaces of double curvature. The peening elements may be separate members, for example hard steel balls similar to those used in ball-bearings, or may be connected or integral with one another, as for example the convolutions of a helical spring. In accordance with my preferred method, the peening elements are loosely confined in the hollow body to be treated, so that in a static condition they rest on the inner surface of said body. Upon the application of vibrational energy to the hollow body, preferably of a frequency in the sonic range, i. e. in the range of audible sound, the peening elements and the wall of the hollow body are activated to produce

40 rapidly recurring impacts of the peening elements with the inner surface of the member being treated. The nature of the vibration should be such as to cause relative reciprocating movement of the peening elements, which is predomin-
45 inately at substantially right angles to the inner surface of the hollow member rather than sliding or tangential motion. The rapidly recurring impacts of the peening elements quickly and effectively peen the inner surface of the hollow member. By effecting relative movement of the member being treated and the peening elements to cause the elements to strike in different places on successive impacts, the entire area to be treated can be peened either uniformly or differentially, as desired. For example, the member can be turned while being vibrated so that different areas are successively presented to the action of the peening elements and the individual elements are caused to strike the surface
50 at different points. The intensity of the peen-

ing action may be controlled by the frequency and amplitude of vibration and by the nature of the peening elements and the duration of treatment. The peening of the inner surface of the member is thus subject to full and effective control.

In the accompanying drawings there is shown by way of example, apparatus for peening the inside surface of a pipe or tube 10. The apparatus shown in Figs. 1 to 3 comprises peening elements disposed inside the tube, and means for supporting the tube for reciprocatory vibration, and for applying vibrational energy to the tube while thus supported. Means is also provided for rotating the tube while being vibrated, so that the inside of the tube is peened throughout its peripheral extent. While the functions of supporting, vibrating and rotating the tube may, if desired, be performed by individual means, the embodiment of the apparatus illustrated in the drawings provides unitary means for concurrently performing all three functions.

By reference to Fig. 1, it will be seen that the tube is supported by a plurality of units, indicated generically by the reference numeral 11. These units are preferably identical with one another and are set at spaced points to support the tube throughout its length. Each of the units 11 comprises means for resiliently supporting the tube, and means for supplying periodic impulses to set the resiliently supported tube in vibration. The resilient support is provided by one or more elongated resilient members 12, shown in the form of a stack of bars of rectangular cross section. The bars 12 are held firmly at their ends by a suitable frame or housing 13. The central portion of the bars is free to vibrate and carries a clamp or yoke 14 provided with a bearing 15 for holding the tube being treated. The yoke 14 also carries the armature 16 of an electro-magnetic motor, the stator 17 of which is mounted on the frame or housing 13, for example, by means of downwardly extending brackets 18. Vertical adjustment of the stator 17 to vary the gaps between the stator and the armature is provided by adjusting screws 19.

Provision is made for supplying alternating or pulsating electric current of the desired frequency to the electromagnetic motor, to apply periodic impulses to the armature 16 and thereby produce vibratory movement of the resiliently supported tube 10. The frequency of the current is correlated to the natural frequency of vibration of the vibratory system, comprising the resilient members 12, the yoke 14 and tube 10, to produce vibratory movement of the desired amplitude. Preferably the electric current is supplied by a source of variable frequency so that the frequency can be adjusted to the natural frequency of the resiliently supported tube or other member being treated. The amplitude and frequency of vibration of the tube should be sufficiently high that the acceleration of the tube is greater than gravity. The vibratory motion of the tube produced by the apparatus shown in the drawings is reciprocating motion in a direction crosswise of the tube.

The transverse vibration of the tube activates the peening elements disposed inside the tube, and produces rapidly recurring impact of said elements with the inner surface of the tube. In the embodiment illustrated in Figs. 1 to 3 of the drawings, the peening elements comprise the convolutions of a spiral spring 20, which extends throughout the length of the tube. The convolu-

tions of the helical spring 20 provide peening surfaces of double curvature similar to the surface of a peening hammer. The flexibility of the spiral spring core assures contact of the convolutions of the spring with the inner surface of the pipe throughout its length, despite any slight irregularity in the surface. At the same time, the action of the spring tends to smooth out any irregularities, to produce a more even surface. The helical spring 20 is of a lesser diameter than the inner diameter of the tube and is confined loosely in the tube, so that it rests freely on the lower inside surface of the tube in static condition. Vibration of the tube by means of the units 11 described above, transmits vibrational energy to the helical spring, so that the spring is also caused to vibrate. The reciprocatory vibration of the tube in a direction transverse to its axis, causes the peening elements to strike the tube at approximately right angles to its surface. A true peening action is thereby produced without excessive scouring or abrasion. As the peening elements are distributed throughout the length of the tube, and as the tube is vibrated throughout its length by the units 11, the inner surface of the tube is peened simultaneously from one end to the other. By rotating the tube about its longitudinal axis, all portions of the inner surface of the tube can be quickly and effectively peened.

In the preferred embodiment of my invention, the tube is automatically rotated while being vibrated. As shown in Figs. 1 to 3, rotation of the tube is produced by extremely simple mechanism comprising a flexible strap 21 extending up over the tube held in the bearings 15, and having one end 22 of the strap anchored to the frame of the unit 11. A yielding downward pull is exerted on the other end of the strap 21 by a spring 23. The strap 21, while sufficiently flexible to conform to the tube, is preferably substantially non-extensible, and is either provided with a friction lining or is made of material providing suitable frictional engagement with the surface of the tube. By reason of this frictional engagement and the manner in which the strap is anchored solidly at one end and resiliently at the other, vibration of the tube by the units 11, results in concurrent rotation of the tube about its longitudinal axis.

While the bearings 15 may, if desired, completely surround the tube, they are shown as half bearings, since the strap 21 serves as the upper half of the bearings as well as the means for rotating the pipe. The spring 23 should be sufficiently strong to hold the tube firmly seated on the bearings 15. The strap 21 is preferably provided with a quick acting fastening device at one end or the other, for example, at the end held by the spring 23, so that the straps can be released to permit removal of a tube after treatment and the insertion of a new tube. The combination of the half bearings 15 and the straps 21, thus provides for rapid loading and unloading of the apparatus.

The rotation of the tube 10 concurrently with its vibration results in peening the inner surface throughout the length of the tube and throughout its peripheral extent. The entire inner surface of the tube is thus uniformly peened. However, it will be understood that by controlling the rotation of the tube and the position of the peening elements, the peening action may be confined to selected areas, or certain portions of the surface may be peened more than others.

5

It will be seen that as the tube 10 is rotated during its vibration, the flexible core 20 is also rotated by its engagement with the tube. The relation between the outer diameter of the helical spring 20 and the inner diameter of the tube is preferably such that different portions of the helical convolutions strike the inner surface of the tube on successive revolutions. This relative movement of the tube and the spring is equivalent to relative movement in a longitudinal direction, so that the points of contact are continually shifted and the formation of distinct rings or depressions in the inner surface of the tube is avoided. Preferably the inner diameter of the tube should be other than an integral multiple of the outer diameter of the helical spring 20. If desired, the peening elements can be moved axially of the tube during vibration, for example, by inclining the direction of vibration of the tube to its longitudinal axis, so that the peening elements are moved axially of the tube by its vibration.

By using the required number of supporting and vibrating units 11, a tube of any desired length may be peened by the apparatus in accordance with the present invention. Preferably the units are supported in such manner that they can be moved to vary the spacing between them. For example, in treating a heavier tube, it may be desired to have the units closer together. The units are preferably mounted on vibration insulating supports, for example, shear type insulators, as illustrated at 24, to reduce the transmission of vibration to the foundation.

The nature of the peening elements in the tube may be varied as desired. In Fig. 4, there is shown an embodiment of my invention in which the peening means comprises a helical spring 20 which is weighted or loaded by an inner core 25, to increase its effectiveness. The inner core 25, may for example, be in the form of a rod, a hollow tube, or another spring.

In Figs. 5 and 6, there is shown a further form of my invention in which the peening means comprises a multiplicity of spherical balls 26. The balls 26 are preferably formed of hard, elastic material, such as steel, and may for example be similar to the balls used in ball bearings. The tube is partially filled with the balls, leaving room for vibratory movement of the balls inside the tube. A suitable cap 27 secured in place by set screws or other fastening means 28 is provided on each end of the tube to retain the balls in the tube. Alternatively, a stream of balls may be caused to flow progressively through the tube, being fed in at one end and discharged at the other.

By reason of the resilient nature of the peening means inside the tube, whether in the form of individual balls, a helical spring, or other means, the peening elements are set in vibration by the vibratory reciprocation of the tube. As the impact elements are loosely confined in the tube, and free to move therein, their vibratory motion is largely determined by their own natural frequency of vibration. The frequency of vibration of the impact or peening elements is preferably different from that of the tube, so that the tube and the impact elements vibrate out of step and continually collide with one another. By suitably selecting the proportions and material of the peening elements, their natural frequency of vibration, may be made higher than that of the tube, so that a still greater number of impacts is obtained.

The amplitude of vibration of the peening ele-

6

ments may also be greater than the amplitude of vibration of the tube, since the peening elements may have greater freedom of movement than the tube. The increased amplitude of the peening elements results in greater force of impact of the elements with the tube, and hence in still greater effectiveness of the treatment.

While the drawing illustrates the peening of a straight tubular member, it will be understood that the method and apparatus in accordance with my invention are equally applicable to the peening of other hollow members including those of irregular shape. It will also be understood that the invention is in no way limited to the particular apparatus shown by way of example in the drawings, but may be varied as desired within the scope of the appended claims.

What I claim and desire to secure by Letters Patent is:

- 20 1. A method of peening the inner surface of a hollow member, which comprises introducing peening elements in said hollow member and vibrating said member to produce repeated impact between said peening elements and the inner surface of said member.
- 25 2. A method of peening the inner surface of a hollow member, which comprises introducing peening elements in said hollow member, vibrating said member to produce repeated impact between said peening elements and the inner surface of said member, and turning said member during treatment to subject different portions of said surface to the peening action of said elements.
- 30 3. A method of peening the inner surface of a hollow member, which comprises introducing peening elements in said hollow member, vibrating said member to produce repeated impact between said peening elements and the inner surface of said member, and producing relative movement between said member and elements to cause said peening elements successively to strike different portions of said surface.
- 35 4. A method of peening the inside of a tube, which comprises introducing peening elements in said tube and vibrating said tube to produce repeated impact between said peening elements and the inner surface of the tube.
- 40 5. A method of peening the inside of a tube, which comprises introducing peening elements in said tube, vibrating said tube to produce repeated impact between said peening elements and the inner surface of the tube, and concurrently rotating said tube.
- 45 6. A method of peening the inside of a tube, which comprises introducing peening elements in said tube and imparting reciprocatory vibratory motion to said elements to produce repeated impact between said elements and the inner surface of the tube.
- 50 7. A method of peening the inside of a hollow member, which comprises placing inside said member a plurality of peening elements having impact surfaces of double curvature and vibrating said member to produce repeated impact between said peening elements and the inner surface of said member.
- 55 8. A method of peening the inside of a hollow member, which comprises introducing peening elements inside said member and vibrating said member at a frequency in the sonic range, to produce repeated impact between said peening elements and the inner surface of said member.
- 60 9. A method of peening the inside of a tube, which comprises introducing peening elements

inside said tube, said peening elements being distributed throughout the length of the tube, and vibrating the tube throughout its length to produce repeated impact between said peening elements and the inner surface of the tube.

10. A method of peening the inside of a tube, which comprises placing in said tube a flexible core having a plurality of peening surfaces, and vibrating said tube to produce relative reciprocatory movement between said tube and core, and repeated impact of said peening surfaces with the inner surface of said tube.

11. A method of peening the inside of a tube, which comprises placing in said tube a helical spring of lesser diameter than the inside diameter of said tube, and vibrating said tube to produce repeated impact between the convolutions of said helical spring and the inner surface of said tube.

12. A method of peening the inside of a tube, which comprises rotatably supporting said tube, introducing peening elements in said tube, and vibrating said tube to produce repeated impact between said peening elements and the inner surface of the tube, and concurrently produce rotation of said tube.

13. A method of peening the inside of a tube, which comprises placing in said tube a helical spring of lesser diameter than the inside diameter of said tube, vibrating said tube to produce repeated impact between the convolutions of said helical spring and the inner surface of said tube, and rotating said spring and tubes at different rates to vary the points of impact.

14. A method of peening the inside of a hollow member, which comprises introducing peening means into the interior of said member, applying vibrational energy to said member and to said peening means to produce reciprocatory vibration of, and impact between, said means and said members, the natural frequency of vibration of said peening means being different from the frequency of vibration of said hollow member.

15. A method of peening the inside of a hollow member, which comprises introducing peening means into the interior of said member, vibrating said member and thereby producing reciprocatory vibration of said peening means and impact of said peening means with the inner surface of said member, the amplitude of vibration of said means being greater than the amplitude of vibration of said member.

16. A method of peening the inside of a hollow member, which comprises loosely confining a multiplicity of spherical balls in said member and vibrating said member to produce impact between said balls and the inner surface of said hollow member.

17. Apparatus for peening the inside of a tube, which comprises peening elements adapted to be inserted in said tube and a plurality of units co-operating to vibrate said tube throughout its length to produce repeated impact between said peening elements in the tube and the inner surface of said tube.

18. Apparatus for peening the inside of a hollow member, which comprises peening elements adapted to be inserted in said tube, means for vibrating said member to produce repeated impact between said peening elements in the tube and the inner surface of said member, and means for rotating the member being treated.

19. In apparatus for peening the inside of a tube, the combination of peening elements

adapted to be inserted in said tube, a bearing for supporting the tube, means for vibrating said bearing to apply vibrational energy to said tube and produce impact between said peening elements and the inner surface of said tube, and means for rotating said tube during vibration, comprising a flexible member anchored at one end and extending around said tube, and resilient means acting on the other end of said flexible

5 member to urge said member into frictional contact with said tube.

10. Apparatus for peening the inside of a hollow member, which comprises peening elements having smooth impact surfaces and adapted to be inserted in said hollow member, and means for vibrating said hollow member to produce repeated impact between said peening elements and the inner surface of said member.

15. In apparatus for peening the inside of a tube, the combination of peening elements adapted to be inserted in said tube, a half bearing for supporting the tube, means for vibrating said bearing to apply vibrational energy to said tube and produce impact between said peening elements and the inner surface of the tube, and a flexible member extending over said tube to hold said tube in said half bearing and to rotate said tube while being vibrated.

20. In apparatus for peening the inside of a tube, the combination of peening elements adapted to be inserted in said tube, means for vibrating said tube to produce repeated impact between said peening elements and the inner surface of the tube and actuated by said vibratory motion of the tube to rotate the tube about its longitudinal axis while being vibrated.

25. In apparatus for peening the inside of a tube, the combination of a spiral spring of lesser diameter than the inside diameter of the tube and adapted to extend lengthwise through said tube, and means for vibrating said tube to produce impact between the convolutions of said spiral spring and the inner wall of the tube.

30. In apparatus for peening the inside of a tube, the combination of a spiral spring adapted to be inserted lengthwise in said tube, a core inside said spiral spring, and means for vibrating said tube to produce impact between the convolutions of said spring and the inner surface of the tube.
